Primary Examiner — George D. Kirschbaum*Assistant Examiner* — Clesse Moore, Jr.(74) *Attorney, Agent, or Firm* — Woods Oviatt Gilman LLP; Katherine H. McGuire, Esq.(57) **CLAIM**

The survival suit, as shown and described.

DESCRIPTION

FIG. 1 is a front perspective view of a survival suit showing my new design;

FIG. 2 is a front, elevational view thereof;

FIG. 3 is a rear, elevational view thereof;

FIG. 4 is a side, elevational view thereof;

FIG. 5 is a side elevational view thereof opposite the view of FIG. 4;

FIG. 6 is a top, plan view thereof;

FIG. 7 is a bottom, plan view thereof;

FIG. 8 is the view of FIG. 1 showing the sleeves in their stowed positions;

FIG. 9 is a front, elevational view of FIG. 8;

FIG. 10 is a rear, elevational view thereof;

FIG. 11 is a side, elevational view thereof;

FIG. 12 is a side, elevational view thereof opposite the view of FIG. 11;

FIG. 13 is a top, plan view thereof;

FIG. 14 is a bottom, plan view thereof; and,

FIG. 15 is a perspective view thereof showing the survival suit in its rolled-up condition.

The broken lines shown illustrate portions and environment of the survival suit that form no part of the claimed design. The diagonal dash-dot lines illustrate stitching that forms part of the claimed design.
